Primary Examiner — Jeffrey D Asch(74) *Attorney, Agent, or Firm* — Morgan, Lewis & Bockius LLP(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front view thereof showing the state that during operation, a circular indicator at the front-lower part has been lit.

The broken lines shown in the figures that are immediately adjacent to the shaded areas and define unshaded and uninterrupted regions represent the bounds of the claim. The circular broken line feature at the top shows environment that is superimposed on a continuous surface. The broken lines form no part of the claimed design.

1 Claim, 7 Drawing Sheets(56)
